UNITED STATES PATENT OFFICE.

ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

Application filed May 5, 1922. Serial No. 558,741.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms, and more particularly to that type of feeler mechanisms wherein the feeler moves in a direction longitudinally of the shuttle to call the change of filling.

In feeler mechanisms of the above general type, it sometimes happens that the teeth of the feeler fail to engage the filling with sufficient positiveness to hold the feeler from movement in a direction longitudinally of the shuttle even though a working supply of filling is present. In such case the filling replenishing mechanism will be set in operation and the filling will be changed in the shuttle notwithstanding the fact that the filling is not substantially exhausted. This liability of the feeler to move longitudinally of the shuttle when a working supply is present is due to a variety of causes. In the first place, the filling strikes the feeler a blow as the lay beats up, and this is liable to cause the feeler to jump without the teeth thereof coming into holding engagement with the filling. Moreover, as the filling is gradually depleted in the shuttle, the feeler may engage the cone end portion of the filling and where the feeler is of the side swipe type, the incline surface is liable to free the feeler to its longitudinal movement. This is particularly observable in some types of filling carriers.

An important feature of the present invention, therefore, consists of a feeler which is mounted for movement in a direction longitudinally of the shuttle to call the change, and which is provided with a main and an auxiliary feeler tip so constructed and arranged that under normal working conditions the main feeler tip alone engages the filling in the shuttle, but should the feeler improperly or prematurely move in a direction longitudinally of the shuttle, when a working supply of filling is present, then the auxiliary tip comes into play and serves to

hold the feeler from movement longitudinally of the shuttle to call the change.

In the drawings:

Figure 1 is a plan view of a feeler mechanism containing the present invention, some of the parts being omitted or broken away, and showing the feeler under normal working conditions;

Fig. 2 is a plan view similar to that of Fig. 1, showing the main tip of the feeler as having failed to hold the feeler from movement longitudinally of the shuttle, and the auxiliary tip in engagement with the filling and holding the feeler from such movement;

Fig. 3 is a detached detail showing the feeler in dotted lines as having moved longitudinally of the shuttle when the filling is substantially exhausted, the teeth of the auxiliary tip under such conditions not coming into contact with the filling carrier or bobbin;

Fig. 4 is a detached perspective detail showing the main and auxiliary feeler tips and the means for relatively adjusting them.

The replenishing mechanism, and the details of the train of mechanism between the feeler and the replenishing mechanism for effecting replenishment of filling when the feeler partakes of its movement longitudinally of the shuttle, are not herein fully shown and described, because the details of such mechanism form no part of the present invention, and any character of well-known replenishing mechanism may be employed, as well, also, as the train of mechanisms associated with the feeler for causing operation of the replenishing mechanism. Only sufficient of the train of mechanism referred to is shown to make clear the operation of the invention.

The advantages of the present invention are more markedly observable in connection with a side swipe feeler of the inclined type, wherein the feeler is displaced longitudinally of the shuttle by the forward pressure upon it when the filling is substantially exhausted on a detecting beat, and the invention is herein described in connection with such type of feeler, although it is to be understood that the invention may be advantageously employed to secure the results sought by the invention in connection with side swipe feelers of other types.

The feeler stand 1 is provided with the slot 2 through which passes the bolt 3 for

securing the feeler stand to a permanent support such, for instance, as the loom frame or extension of the shipper stand, as usual. The feeler stand has a slide 4 mounted for lateral movement in its rear portion, and as shown, the slide 4 is movable in guideways between the lugs 5, 6 formed on the feeler stand. The slide 4 is provided with a slot 7 through which extends the feeler 8. At its front portion the feeler 8 passes through a swiveled or rocking bearing 9 mounted between a bracket 10 and the feeler stand 1. Between the rear portion of the feeler stand and the swivel or rocking bearing 9 the feeler is provided with a spring 11 and a bridge 12 against which the spring bears, the construction being such that the spring 11 normally holds the feeler in its rearward feeling position.

20 The slide 4 has connected to it at 13 the transmitter 14 which constitutes an element in the train of mechanism between the feeler and the replenishing mechanism for effecting replenishment of filling.

25 The parts so far described are shown as of the same general construction and operation as the feeler mechanism shown and described in the patent to Edward S. Stimpson, No. 1,309,226, dated July 8, 1919.

30 As made clear in the patent to Stimpson, the lay is provided with the usual shuttle-box having in its front wall a slot for the entrance of the feeler. The shuttle 15 is of usual type and carries the filling carrier 16 which is shown as a bobbin, although cop may be employed, if desired. The shuttle 15 is provided with an opening 17 to register with the opening in the front wall of the shuttle-box so that on a detecting beat the 35 feeler may enter the shuttle and feel for the filling 18 wound upon the filling carrier.

The feeler 8 has its rear end portion provided with a main feeler tip 19, the filling engaging portion of the tip being formed with teeth 20 which are preferably made blunt, that they may not injuriously affect the filling on the beat-up.

40 The feeler 8 also carries an auxiliary feeler tip 21 which has teeth of a different character than the teeth of the main feeler tip. As shown, the auxiliary feeler tip 21 is formed of a piece of metal which is mounted on the feeler 8 in separated relation with the main feeler tip. The auxiliary feeler tip 45 may be conveniently formed of a piece of metal formed as a sleeve and mounted for adjustment toward and from the main feeler tip. As shown, the auxiliary feeler tip 21 has its upper and lower portions united by 50 a set screw 22, Fig. 4, so that by loosening the screw 22 the auxiliary feeler 21 may be adjusted toward or from the main feeler tip 19 and held in adjusted position by setting up the screw 22.

45 The main and auxiliary feeler tips are

preferably separated by a smooth untoothed portion 23 of the feeler between the teeth 21 of the main feeler tip and the teeth of the auxiliary feeler tip.

50 Since the auxiliary feeler tip is to act promptly and with positiveness on the filling to hold the feeler from movement longitudinally of the shuttle when a working supply of filling is present, and the main feeler tip has failed to hold the feeler, the teeth of the auxiliary feeler tip are formed sharper than the teeth of the main feeler tip. In the present instance the auxiliary feeler tip has teeth 24 formed somewhat like saw teeth and facing toward the main feeler tip. 55 Where the auxiliary feeler tip is formed as a sleeve and mounted upon the feeler, the two portions clamped together by the screw 22 may each be provided with teeth so as to form two rows and further insure positiveness of action.

Under normal working conditions, as indicated in Fig. 1, the main feeler tip alone will engage the filling in the shuttle and the teeth of the main feeler tip will ordinarily 60 sink into the filling so that the feeler may be held from movement longitudinally of the shuttle by the filling. Under such normal working conditions the auxiliary feeler tip does not engage the filling as indicated in Fig. 1, and the relation of the main and auxiliary feeler tips is such that even when the filling is substantially exhausted on a detecting beat, as indicated in Fig. 3, and the feeler moved longitudinally 65 along the filling carrier, as indicated by dotted lines, the auxiliary feeler tip does not engage the filling carrier and therefore does not injure it by sliding movement thereof.

70 This operative relation of the main and auxiliary feeler tips will vary, of course, in accordance with the conditions of use, but usually the auxiliary feeler tip will have its teeth not only separated from the teeth of the main feeler tip, but located forwardly 75 thereof with respect to the longitudinal axis of the shuttle. Ordinarily the teeth of the main feeler tip will serve to act reliably to hold the feeler from movement longitudinally of the shuttle when a working supply 80 of filling is present on a detecting beat; but sometimes it may fail to perform this function, and especially is this fact noticeable when the conical portion *a* of the filling is presented to the main feeler tip. The forward pressure of the inclined conical portion *a* of the filling against the main feeler tip and under the impact or blow, is liable 85 to displace the feeler longitudinally of the shuttle, in which case the auxiliary feeler tip will come into action and engage the filling, as indicated in Fig. 2, before the feeler has moved sufficiently far to call the change.

90 On the succeeding beat of the lay of the course the feeler will be returned to its nor- 95

mal feeling position and again the main feeler tip will act upon the filling. Should it again be displaced longitudinally by the frontward impact, the teeth of the auxiliary feeler tip will come into action and prevent replenishment of filling. The extent of the smooth untoothed portion 23 between the teeth of the main feeler and the teeth of the auxiliary feeler may of course be varied, 10 but it is desirable in most cases that the plain untoothed portion shall be sufficient and be curved in a manner to cause the teeth of the auxiliary feeler tip to engage the filling only when the main feeler tip fails to 15 be engaged by the filling and held from movement longitudinally of the shuttle.

By making the auxiliary feeler tip adjustable relative to the main feeler tip, the feeler may readily be adapted for use in connection with different kinds of filling, and by forming the teeth of the auxiliary feeler tip sharper than the teeth of the main feeler tip, no injury is done the filling, because the teeth of the auxiliary feeler tip come into 25 action only occasionally and then should act quickly and promptly.

What is claimed is:

1. A feeler mechanism for looms having a side slipping feeler which is provided with 30 a main feeler tip having teeth which normally engage the filling in the shuttle on a detecting beat, and an auxiliary tip having

teeth which engage the filling on a detecting beat only in case the main feeler tip fails to hold the feeler from side-slipping movement as the lay beats up, means for securing the auxiliary tip in fixed adjusted position relative to the main feeler tip that the teeth of the two tips may extend variable distances rearwardly and means for effecting 40 replenishment of filling when neither feeler tip holds the feeler from slipping longitudinally along the filling carrier on a detecting beat.

2. A feeler mechanism for looms having 45 a side slipping feeler which is provided with a main feeler tip having teeth which normally engage the filling in the shuttle on a detecting beat, and an auxiliary tip having teeth which engage the filling on a detecting 50 beat only in case the main feeler tip fails to hold the feeler from side-slipping movement as the lay beats up, a clamp carrying the auxiliary feeler tip and adjustably secured to the main feeler that the teeth of the two 55 tips may be placed in different relative rearward positions and means for effecting replenishment of the filling when neither feeler tip holds the feeler from slipping longitudinally along the filling carrier on a detecting beat.

In testimony whereof, I have signed my name to this specification.

ISAAC SNOW.
